United States Patent Office

Des. 176,262
Patented Dec. 6, 1955

176,262

PLATE OR SIMILAR ARTICLE

Takeshi Inoue, Atsuta-ku, Nagoya, Japan

Application November 29, 1954, Serial No. 33,266

Term of patent 7 years

(Cl. D44—15)

The figure is a plan view of a plate or similar article, showing my new design.

The plate is of a conventional configuration when viewed from the side and bottom thereof.

I claim:

The ornamental design for a plate or similar article, substantially as shown and described.
